UNITED STATES PATENT OFFICE

VENO L. PISTOCO, OF WICHITA FALLS, TEXAS

METHOD OF AFFIXING LETTERING TO WOVEN MESH FABRIC

Application filed August 10, 1926, Serial No. 128,500. Renewed February 23, 1929.

This invention relates to an improved method of permanently affixing lettering to mesh surfaces, and its principal object resides in affixing lettering to woven wire mesh, coarse Swedish organdies, mosquito netting and similar fabrics for the purpose of advertising or designing.

The invention further contemplates the provision of such a method by which lettering, designs and the like may be applied, for example, on the screen doors of mercantile establishments either in positive style or phantom, the latter sometimes being preferable in cases where ventilation is essential through the door, especially when the design or lettering is required to be of considerable size.

A particularly important object of the invention resides in the forms of application of lettering by which the latter is made to either adhere to the object processed to produce positive lettering or to remove a major portion of the lettering to obtain a phantom effect.

With these principal objects in view, the invention consists still further of lesser objects, which will become apparent as the description proceeds, taken in connection with the accompanying drawings, wherein:

Figure 1 is a representation of the improved method of lettering advanced by the present invention exemplified on an ordinary screen door.

Figure 2 is a representation of the phantom type of lettering involved in the invention, and

Figure 3 shows the manner of removing the backing employed in applying the embossed on positive lettering.

In proceeding further with the invention, it may be stated that the kind of paint or pigment used in practicing the invention is optional, the only requirement being that the same must be composed of a viscous body of comparatively heavy consistency, and it will be further understood that at no time is it required to use any kind of composition to fill the interstices between the strand composing the woven mesh, prior to applying the characters, as this is unnecessary as will presently become apparent.

While as stated, the invention is particularly valuable in applying lettering to screen doors and windows of stores, it is not essentially restricted to such use, its application being equally as effective in many other cases, hence the drawing illustrates as a subject an ordinary wire mesh sheet 1 having a frame 2.

Describing primarily the character of lettering represented in Figure 1, known as embossed or positive, a suitable backing 3, consisting preferably of a layer of fine tissue paper, light Japan silk, felt or waxed paper, is applied on the opposite side of the mesh from the side to be processed. The lettering 4 is then applied in substantially the same manner as done on smoother surfaces.

When the paint has become nearly dry, the lettering 4 is dusted with a quantity of dry chalk or powder and the latter thoroughly rubbed into the surface of the lettering to present a smooth and even appearance. When thoroughly dry, the backing 3 is peeled off as shown in Figure 3, the paint remaining intact upon the screen, as shown in Figure 1, with comparative durability and permanency.

Now, the method of attaining the phantom effect of lettering exemplified in Figure 2, does not depart materially from that set out in the foregoing, but since the majority of paint applied must be removed from the screen to obtain this effect, it is necessary to employ as a backing a piece of porous material such as wood in substitution of the felt or other backing 3. The wood backing is placed snugly against the material to be processed to restrain the paint from running. While the latter is applied as previously set forth, the paint thus adheres to the wood surface through the screen, and is permitted to set until nearly dry, whereupon the backing is carefully removed from the screen, taking with it the greater part of the paint, there remaining on the intercrossing strand composing the screen, portions of the paint defining lettering in a shadowy effect. In this manner, the circulation of air is not interfered with, yet the sign produced thereby is perfectly visible.

It is of course obvious that different colors

may be used in the letters or designs, both in applying the embossed type or phantom type, and may be so arranged to produce a color scheme of pleasing appearance.

5 What is claimed is:

A method of applying lettering and designs on open mesh to obtain a shadowy effect consisting in placing a backing of wood or the like against said mesh and in applying paint 10 in liberal quantities through said mesh to define lettering on said mesh and backing, then in permitting said paint to attain a semi-dry state and finally in removing said backing and adhering paint to define on said screen a 15 suggestion of lettering.

In testimony whereof I affix my signature.
VENO L. PISTOCO.
